US00D941617S

(12) **United States Design Patent** (10) **Patent No.:** **US D941,617 S**
(45) **Date of Patent:** **** Jan. 25, 2022**

(54) **CHEST**

(71) Applicant: **Iris Ohyama Inc.**, Sendai (JP)

(72) Inventor: **Susumu Kobayashi**, Kakuda (JP)

(73) Assignee: **IRIS OHYAMA INC.**, Sendai (JP)

(**) Term: **15 Years**

(21) Appl. No.: **29/719,785**

(22) Filed: **Jan. 7, 2020**

(30) **Foreign Application Priority Data**

Aug. 9, 2019 (JP) 2019-017961

(51) **LOC (13) Cl.** **06-04**
